UNITED STATES PATENT OFFICE

MARION F. BURGETT, OF INDIANAPOLIS, INDIANA

METAL WORKER'S RAPID SPACER

Application filed November 26, 1930. Serial No. 498,273.

The object of this invention is to provide a device for the use of metal workers in dividing surface lines into numerous equal spaces, as for example, locating the rivet points in a flat piece of sheet metal of right dimensions to make a cylinder or pipe four inches in diameter so the holes in one section will register with those in the next when assembled together. The object also is to appropriately stamp the device with a series of pipe diameters and corresponding sheet lengths.

I accomplish the above and other objects which will hereinafter appear, by the device illustrated in the accompanying drawing, in which

Fig. 1 is a top plan view of my invention in nearly folded condition;

Fig. 2 shows the device applied for use in marking off the rivet holes in a sheet of material cut to dimensions for a four inch pipe; and

Fig. 3 shows the same sheet after the places for the rivet holes are marked thereon by the use of my invention.

Like characters of reference indicate like parts in the several views of the drawing.

The body or frame of my device comprises a series of top bars, here shown as fourteen in number, the two end ones of which are substantially one half of the length of those between. It also comprises a like number of bottom bars. The long top bars cross the long bottom bars at their ends and middles and are pivotally united in pairs, at their middles, by rivets *a*. The inner ends of the top short bars are pivotally united to the adjacent ends of the short bottom bars. The outer ends of the bottom short bars are pivotally united by rivets *b* with the outer ends of their respective nearest long top bars, and the outer ends of the next long top bars are likewise pivotally connected with the ends of the next bottom long bars and so on until both ends of all of the long bars are pivotally connected with the corresponding ends of the corresponding long bottom bars, making a lazy tongs structure.

The rivets in the ends of the bars are all the same distance from the middle rivets of

their respective bars. The top bars are permanently numbered consecutively from "0" to "12", beginning with the first long bar. These numbers indicate the diameters in inches of round pipes which can be made from a sheet of a length in inches which is stamped on the same bar. For example, a 4 inch pipe will require a sheet $12\frac{9}{16}$ inches long when the edges are to be contacted and edge-welded. The numbers on the bars give the net dimensions without any allowance for laps or seams, to such degree of accuracy as is required by sheet metal workers who use a common rule and not a decimal or finely graduated scale. When lap or lock seams are to be made the trade skill of the workmen will enable him to add the corresponding additional measurements.

If desired, the bars may be numbered on both ends.

Holes *c* are punched through the midwidth of the bars and midway between their ends and middle pivots to aid in marking surfaces.

The dimensions of the bars in length, width and thickness, will be varied to suit the size of the work to be spaced, and the number of bars may also be varied for the same reason.

In the example shown in Figs. 2 and 3, it is desired to lay off a flat metal sheet *d* of right length to make a pipe four inches in diameter and to mark the points for holes for rivets to unite this section with other similar sections. The workman by reference to bar marked 4", which is the desired pipe diameter, is informed by the number $12\frac{9}{16}$ " also marked on that bar, of the length of sheet required to make a 4 inch pipe, and he lays out and cuts off the metal sheet *d* accordingly. Then he draws a line *e-f* parallel with one of the long edges of the sheet, at a distance from that edge equal to the distance therefrom of the centers of the desired holes.

My spacing device is then expanded and laid upon the sheet *d*, with the right edge of bars 0 and 4 at the respective ends of the line *e-f*. As a check the ends of the sheet *d* should be visible through and bisect the holes *c* in the bars 0 and 4. Then the locations of

100

the rivet holes all along the line *e-f*, are marked by drawing cross lines, using the right edges of bars 1, 2 and 3 as straight edges. Upon removal of the spacing device the sheet 6 *d* will appear as shown in Fig. 3 wherein the location of the rivet holes will be designated at the crossing of line *e-f* by the short diagonal lines.

Having thus fully described my invention 10 and its manner of use, what I claim as new and wish to secure by Letters Patent, is—

1. In a device for laying off equal spaces, a plurality of upper and lower bars, the upper bars crossing the lower bars at their ends 15 and middles, pivotal connections between the bars at their crossing places in the manner of a lazy tongs structure, each of said top bars being formed with numbers increasing consecutively in value from bar to bar designating pipe diameters and all of said bars being formed with eight holes through their midwidths midway between their end and middle pivots.
2. In a device for laying off equal spaces, 25 a plurality of upper and lower bars, the upper bars crossing the lower bars at their ends and middles, pivotal connections between the bars at their crossing places in the manner of a lazy tongs structure, each of said top bars 30 being formed with numbers increasing consecutively in value from bar to bar, said numbers designating pipe diameters and having circumference measurements for each diameter on the respective bars and all of 35 said bars having eight holes through their midwidths midway between their end and middle pivots.

In testimony whereof I affix my signature.
40 MARION F. BURGETT.
